UNITED STATES PATENT OFFICE.

T. THEODOR COHEN, OF PHILADELPHIA, PENNSYLVANIA.

VENTILATING BULK-WINDOWS, STORES, &c.

SPECIFICATION forming part of Letters Patent No. 341,318, dated May 4, 1886.

Application filed January 2, 1886. Serial No. 187,471. (No model.)

To all whom it may concern:

Be it known that I, T. THEODOR COHEN, of Philadelphia, Pennsylvania, have invented and produced a new Improvement for the 5 Ventilation of Bulk-Windows, Stores, Offices, or Dwelling-Houses, of which I annex drawings and full description.

This invention relates to devices for ventilating bulk-windows, stores, offices, and other 10 apartments; and it consists in novel means for hanging a shutter or valve above the window glass or sash, as will be fully understood from the following description, when taken in connection with the annexed drawings, in 15 which—

15. Figure 1 is an inside elevation of a window-frame and window having my improved ventilator applied to the same and closed. Fig. 2 is a similar view of the same parts, showing 20 the ventilator open. Fig. 3 is a vertical central section through Fig. 1. Fig. 4 is a similar view of Fig. 2. Fig. 5 is an inside view of 25 one of the end pivotal holders for the ventilator-plate. Figs. 6 and 7 are front and top views, respectively, of one of the said holders. Fig. 8 shows one of the slotted bearing-plates 30 for the pivots of the holders. Fig. 9 shows an adjusting-rod and its thumb-screw, and Fig. 10 is a view of the perforated plate *h*.

30. In the annexed drawings, *A* designates a window-frame, in which is applied the window-plate *B*, above which is my improved ventilator, which is constructed in the following manner: *C* designates a window-plate, 35 which, with its end holders, is designed to close the space left between the upper edge of the plate *B* and the lintel of the window-frame *A*, as shown. The holders *D D* for the plate *C* consist of side wings, *b b*, formed on 40 which are gudgeons or pivots *b'*, the narrow vertical angular portions *b²*, and angular lips or stirrups *b³*, which latter support the ventilator-plate *C*, as shown in Figs. 3 and 4. In front of the plate *C*, and secured by screws 45 *e e* to the wings *b b*, are plates *F*, having flanges *c*, between which and the angular portions *b²*

of the said wings grooves *d* are left, in which the ends of the ventilator-plate *C* are received and confined. The gudgeons or pivots *b'* of the holders *D D* are supported in bearing-plates *k*, rigidly secured to the inner sides of the uprights of the window-frame *A*, and constructed with slots *l*, which readily allow the application and removal of the ventilator. From the upper angle of one of the plates *b* projects an arm, *b⁴*, to which is suitably attached a rod, *G*, adapted to be secured to a perforated screw-tapped plate, *h*, by means of a thumb-screw, *g*.

It will be seen from the above description 60 that I employ a narrow glass section, *C'*, above the upper terminus of the window-plate *C*, which section can be vibrated on its end bearings and secured by the screw *g* at any desired angle, according to the size of the opening required for ventilation. It will also be observed that the ventilator-plate *C* can be readily removed from and applied to its holders; 65 also, that I provide a strip, *a*, of rubber or other suitable packing across the top of the 70 glass, to prevent the entrance of water while washing the same from the outside.

Having described my invention, I claim—

1. The holders *D D*, each composed of a wing, *b*, provided with angular flanges *b² b³*, 75 and a pivot, *b'*, in combination with an angularly-flanged portion, *F*, forming a groove, *d*, for receiving the ventilator-plate *C*, substantially as described.

2. The combination, with a window having 80 a ventilating-space above its plate *B*, of a vibrating ventilator pivoted and mounted as described, a packing, *a*, an arm, *b⁴*, on one of the holders, an actuating-rod connected to said arm and provided with a thumb-screw, 85 and a fixed plate, *h*, screw-tapped and secured to the window-frame, all substantially as herein described.

T. THEODOR COHEN.
